UNITED STATES PATENT OFFICE.

ROBERT LARTER, OF NEWARK, NEW JERSEY, ASSIGNOR OF ONE-HALF TO
JOHN B. SCARLETT, OF SAME PLACE.

LOCK-NUT.

SPECIFICATION forming part of Letters Patent No. 556,682, dated March 17, 1896.

Application filed November 28, 1894. Serial No. 530,234. (No model.)

To all whom it may concern:

Be it known that I, ROBERT LARTER, a citizen of the United States, residing at Newark, in the county of Essex and State of New Jersey, have invented certain new and useful Improvements in Lock-Nuts; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to certain improvements in that class of nut-locks in which two nut-like parts or sections, each provided with locking-teeth on their engaging faces, coat with a reversely-threaded bolt or shaft to secure the desired lock, the invention being applicable to bolts, axles, shafts, or similar devices, to railway-joints, vehicles or machinery of any kind.

Heretofore in certain lock-nuts of which I am aware the locking-teeth and contiguous facing surfaces of the said sections were made to conform and coincide each with the other when in locked engagement, and the said surfaces on all sides of the central perforation came in contact. By this construction it was necessary in fastening the parts to first tighten the inner or chief nut against the fish-plate or other part with which the bolt is used, then to bring the second nut near to the first, the teeth of one matching with those of the other, and then to apply a wrench to both nuts and turn them backward together and thus bring them to bear one against the other to secure the desired lock. By this backward movement of the nuts away from the fish-plate or part to be fastened there is a failure in securing the rigidity of fastening generally desired. By my construction I secure the desired rigidity and avoid the necessity of back movement.

The objects of the invention are to secure a more certain and positive fastening of parts, to more perfectly resist the loosening action occasioned by constant jarring, to dispense with spring-washers and thus reduce the cost of fastening, and to secure other advantages

and results, some of which may be referred to in connection with the description of the working parts.

The invention consists in the improved nut-lock and in the arrangements and combinations of parts, all substantially as will be hereinafter set forth and finally embodied in the clauses of the claim.

Referring to the accompanying drawings, in which like letters indicate corresponding parts in each of the views, Figure 1 is a section of a railway-joint, showing the improved nut-lock. Figs. 2 and 3 are plans showing the engaging faces of the two nut-like sections. Figs. 4, 5, 6, and 7 show varieties of the said nut-like sections. Fig. 2^a is a side view of the section, having radial teeth at but one side of the center perforation, and Fig. 8 is a detail showing a form of bolt which is sometimes preferred.

In said drawings, *a* indicates a railway-rail; *b*, the fish-plates thereof; *c*, the bolt uniting said parts, and *d* *e* the lock-nuts arranged on threaded end of said bolt. Said bolt is of reduced diameter at its extremity opposite the head, and is oppositely threaded, the threads *f* of the reduced extremity being of the same number to the inch as those *g* on the larger part of the bolt adjacent to said reduced part. Upon the larger threaded part *g* of the bolt is arranged the section *d*, which is provided on its outer face at one side of the threaded center perforation with a plurality of radial teeth *h*, the opposite side of said face across the perforation being devoid of such teeth and being set back, so that the nut is of reduced thickness to allow a free play or movement of the teeth of the outer nut to allow a tilting of the outer nut, as will be hereinafter described. At one side of the said teeth the same are provided with a long or gentle incline *i*, as shown in Fig. 2^a, and on the other with an abrupt inclination *j*, the first inclination serving to allow a comparatively easy passage of engaging-teeth and the second a more difficult return movement.

The teeth *h* on the section *d* are preferably more than one in number, as indicated in Figs. 2, 4, and 6, the greater the number within a given limit the more nicely the adjustment when the parts are in locked rela-

tion, as will be understood. When in said locked relation the two locking sections do not present meeting surfaces on all sides of the bolt, as in prior devices above referred to, but one of the nuts or sections is materially cut away, as indicated in Fig. 2^a, so that there will be an open space between the nuts or sections at the sides opposite the teeth *h*, and this space admits of a change of inclination of the outer nut with respect to the inner nut when the teeth of the two nuts are forced past one another, such as would not be allowed were the nuts in engagement on all sides of the bolt, as heretofore.

15 The outer nut or locking section, *e*, is also provided with radial teeth of a shape similar to those of the section *d*, but in this case the series extends entirely around the center perforation, and so is adapted to enter into locking engagement at frequent points, so that there will be but little lost movement in securing a lock or return movement after the lock is effected to secure a rigidity of parts.

25 The center of the outer nut around the central perforation is deeply cut or countersunk, as shown at *k*, the recess extending quite a distance back from the toothed faces. This admits of an increased springing of the bolt and coacts with the cut-away portion of the 30 nut *d* in allowing a passage of the teeth *h* over those of the opposite nut or section. The countersink or recess *k* also admits of a greater range of adjustability, in that the nut *e* can pass inward over the shoulder formed by 35 the reduced outer end of the bolt. The resilience of the bolt is increased or rendered more easily effective by reducing the diameter of the bolt between threaded parts, as indicated more clearly in Fig. 8. By the construction described, I am enabled by a strong wrenching force upon the outer nut, *e*, to turn said nut either forward or backward independent of its co-operating nut, and this is rendered more easy because of the opposite 40 inclines *i* and *j*. It is not necessary to back the inner nut against the outer one after said inner nut has been screwed in place against the fish-plate in order to secure an interlocking of parts, but I first secure a proper engagement of the inner nut with said fish-plate 45 50

and then screw the outer nut up to said inner nut and thus effect a locked engagement, the teeth *h* sliding over the continuous series because of the cut-away opening at one side of the bolt and the resiliency of said bolt, all as will be understood.

To unlock the inner nut the outer nut is simply turned in the reverse direction, the abrupt incline of the teeth *h* allowing such reverse movement.

I am aware that nuts have been provided with a single locking-tooth on one side of the center perforation to engage a continuous or regular series of teeth on a co-operating nut; but in the present case I employ a plurality of such teeth and thus secure a different effect in locking, in that the action of the nut is more regular and positive and has less of a certain wrenching effect by which the bolts are broken.

Having thus described the invention, what I claim as new is—

1. The combination with the bolt having a diametrically-reduced part between the differing threads, *f* and *g*, thereof, of a nut having teeth on one side of the bolt-perforation only, and a co-operating nut having a continuous series of such teeth, substantially as set forth.

2. The combination with the bolt, diametrically reduced at its end and having threads *f* and *g*, of nuts or sections *d* and *e* having threads to engage those of the bolt and having teeth on their engaging faces adapted to enter into locking engagement, the teeth of one of said nuts being oppositely inclined, and one of said nuts being cut away out of correspondence with the other, a space being formed between allowing of a change of inclination of one nut to the other and a passage of the oppositely-inclined teeth over those of the co-operating nut, substantially as set forth.

In testimony that I claim the foregoing I have hereunto set my hand this 24th day of November, 1894.

ROBT. LARTER.
